METHOD OF BINDING BOOKS

Walter Meyer, Northport, N. Y.

Application November 8, 1949, Serial No. 126,137

14 Claims. (Cl. 11—1)

This invention relates to a method of binding books and more particularly to the binding of book signatures, and still more particularly to apparatus for carrying out book binding operations.

This application is refiled as a substitute-in-part for my application Serial No. 603,664, filed July 7, 1945, entitled Method of Book Binding, and now abandoned.

My invention is concerned with the carrying out of the binding of books which will effect economies in the time involved for completing such operations and avoid the delay, expense as well as avoiding the need for the storage space involved in book binding processes heretofore employed.

My invention has for its object the provision of a method for effecting the book binding operations in which the elements for uniting a stack of signatures up to the point of "casing-in" may be conducted with economy and speed as obtained by reducing the handling operations while at the same time providing a book binding of great strength and durability.

My invention seeks to avoid the long delay and expense of binding as heretofore practiced, especially with those binding operations employing glue bonds for uniting signatures to the crash or super, backing and head bands, and which operations involve the employment of normally wet adhesive which requires periods of setting and drying between each operation to effect the union of the components of the book.

In accordance with the method for practicing my invention and the apparatus for carrying out such method, a stack of signatures is score-folded to expose the folded and scored edges in a composite edge for forming the book backing, and while under clamping pressure to prevent displacement, the back edge is coated with an adhesive, which is partially dried after application and then simultaneously with the application of the crash and backing, effecting a spreading and setting of the adhesive, whereupon a reactivation of the adhesive through the backing and crash will effect a union of the signature pages with each other and to the backing, by the agency of heat, which also will effect the conversion of the adhesive to an irreversible state of plasticity except at temperatures above 200° F.

More specifically, my invention has for its object the provision of a method for effecting the book binding steps wherein spreading and uniting of the backing adhesive to the bookbinder's crash and backing paper is effected under heat, to be able to proceed directly to the "casing-in" step without delay.

Still further it is an object of my invention to effect economies in book binding and to unite the signatures to each other and to the backing sheet without any alteration in the procedural step with regard to the character of paper employed, to permit similar procedural steps to be carried out whether the paper is porous and absorbent, glazed, calendered, hard coated and variations thereof.

My invention still more particularly has for its object the provision of a method for carrying out book binding steps including the stacking of perforated signatures, the shifting of the edge of a stack of such signatures in echelon while simultaneously setting the adhesive under heat and pressure to effect an intimate distribution of a setting adhesive, uniting the pages constituting the signatures to each other and to other signatures, providing in the book that is formed an intimate union of

2

the pages, free from any defects as to running of adhesive or breakage upon sharp folding, to secure durability and intimacy of bonding of the pages in a manner effected heretofore only by laborious hand sewing operations.

Still more particularly, it is an object of my invention to provide a device for carrying out book binding operations which are effective independently of the character of paper employed and the provision of apparatus for edgewise arranging the folds of signatures in echelon, while setting the adhesive for uniting the signature edges to each other and to the reinforcement comprising the crash and backing elements, to proceed to the stage for "casing-in" without the storage herefore deemed necessary.

Still further it is an object of my invention to provide a method and apparatus which will effect large economies in carrying out the book binding operations.

To attain these objects and such further objects as may appear herein, or be hereinafter pointed out, I make reference to the accompanying drawing forming a part hereof, in which—

Figure 1 is a plan view of a signature before the final fold;

Figure 2 is a magnified fragmentary section of the fold of the signature shown in Figure 1;

Figure 3 is a section taken along the line 3—3 of Figure 2 after folding;

Figure 4 is a section taken along the line 4—4 of Figure 2 after folding;

Figure 5 is a perspective view of a stack of signatures in accordance with my invention;

Figures 6 to 11 are sections showing the progressive steps in carrying out my method;

Figure 12 is a perspective view of apparatus for carrying out the method;

Figure 13 is a magnified fragmentary sectional view taken on the line 13—13 of Figure 12;

Figure 14 is a magnified fragmentary section taken on the line 14—14 of Figure 13.

Summarizing my invention, I provide a method of binding books in which, in the preferred form, a stack of signatures is clamped and under such condition the edge to be bound is coated with a heat settable adhesive.

I prefer to use signatures, the last fold line whereof has been folded upon a perforated line for sharp folding leaving interrupted remnants. The backing strip has the super or crash superimposed thereon, with or without an interposed layer of adhesive, and under such condition of the stack of signatures it is treated simultaneously to distribute the adhesive and to activate the same while spreading the signature edges in a more or less echelon position. This treatment serves to set by heat and pressure the composite of backing strip, crash and the adhesive to the signature edges, uniting the same to the backing strip and integrating the binding to attach all pages of a signature together, and all independent signatures to each other, the simultaneous spreading and setting action avoiding those more prolonged and tedious steps employed in present binding operations.

The invention may be summarized as also providing a machine for binding a stack of perforated signatures, providing apparatus whereby the signature edges are fanned out or formed in echelon while activating to adhesiveness and setting the same by heat and pressure, forming an adhesive film to drive the adhesive into the edges of the pages constituting the signature, and to join groups of signatures to each other and to the crash and backing liner.

Making reference to the drawing, my invention concerns itself with the book binding steps preceding "casing-in".

and involves the initial formation of the usual signatures from the book pages. In the drawing, the open signature 10 is shown disclosing to view the last fold 11, which has been performed by a perforation process to have incised segments 12 separated from connecting webs 13. A stack 14 of such signatures is illustrated in Figure 5, the ends 11 forming the last fold being aligned to form the back 15. The formation of the stack 14 as described presents the initial step of my method of binding wherein the back constitutes a surface which alternates promiscuously and presents for union the serrated edges 16 of the pages as a result of roller perforation employed in making the incision 12, and a series of loops 17 constituting the folded web 13 of the folding process previously described in making each signature.

It will be observed that while the center loop 18 is spaced inwardly from the outer loop 19, the serrated cut edges 16 will tend to bring some of the extreme edges of the center pages more or less in alignment with some portion of the opposed edges of the outermost pages due to the wavy outline of the perforation device employed for making the perforation 12.

In accordance with my method, with a stack arranged as shown in Figure 5, I then position the stack in a clamp whose jaws 20 and 21 hold the stack to expose a section 22 free to hinge or bend in parallelism to the book back above the clamp edges 23. In this position, the edge 15 may remain flat or may be rounded by means of a back former. Thereupon the adhesive binding operation is performed by means of heat activatable, thermoplastic, heat irreversible adhesive at predetermined temperatures. For this purpose the adhesive which I employ is a synthetic resin known on the market as "Akton" synthetic adhesive. This material is an emulsion of a high polymer acetate, constituting polyvinyl acetate in an aqueous suspensoid or vehicle. The emulsion in the aqueous medium is of a viscosity of 250-350 centipoises (viscosity of a solution containing 86 grams of polymerized vinyl acetate in 1000 grams of benzine solution at 20° C.). Plasticizers known for this type of the vinyl polymer and accelerators to form a thermo-setting, heat irreversible resin are also preferably, though not necessarily, included in the film forming emulsion. The adhesive when air dried or force dried leaves a film of permanent flexibility. Under temperatures of approximately 200° F. and pressure to flex the sheet as applied to the air dried film and described hereafter, the film first melts and then sets. Thereafter heat up to 200° F. fails to soften the film and the film is characterized by permanent flexibility and great tensile strength. The film may however redissolve but is irreversible to softening or will not melt at temperatures below 200° F. Upon resorting to air or forced drying step, the residual film before applying the heat and pressure retains sufficient water to activate water soluble adhesives and sizes present in the paper and in the other components of the book comprising glue sized and stiffened crash or super.

The air dried or force-dried film after exercising its glue sized activation under heat and pressure will flow and become plastic, and then will set to be unaffected by heat as to plasticity at temperatures below 200° F. and accordingly is a thermoplastic film above 200° F.

With the adhesive thus described provided, a film layer 24 is applied by brush or transfer roll and then air or force-dried by warm circulating air. Thereupon the layer of book binder's crash or super 25 is applied lightly, as shown in Figure 7. This material is preferably stiffened by a glue or water soluble size. There is then superimposed a backing strip 26, preferably having an air dried film of the Akton adhesive 27, previously described, but which contains a residual amount of water to retain the film in a thermo-plastic condition. The backing strip 26 may be crinkled Kraft paper with the crinkles longitudinal or parallel to the edges of the book and carrying the cloth head-bands adhered thereon. These head-bands may be

applied as part of the process for adhering the paper backs. In this condition the backing is then rubbed by a rolling action beginning at the center of the stack and rolling first in one direction toward one side of the book 5 stack, as shown in Figure 9, applying the heat of about 200° F. and pressure to flex the overhanging 22 longitudinally of the clamp before reversing to the center. The flexing pressure arranges the edge of the signatures in echelon, or to fan them out and in this condition the edges 10 of the pages in each signature, as well as the loops, have the adhesive spread thereover edgewise and in close adjacency to the edge and enter the inner pages of each signature under heat flow. The adhesive film 27 as well as the film 24 are merged through the interstices of the 15 crash or super and the size on the crash activated to adhesiveness to form a compatible bond.

On the return roll toward the center, the opposed face and edges of the overhanging strips are supplied with adhesive and the adhesive film set to the said thermally 20 unaffected state of plasticity at temperatures up to below 200° F., and accordingly is thermoplastic above such temperature. The rolling and spreading operation under flexing pressure is repeated for the other half of the stack in the same manner as shown in Figure 10.

Figure 11 shows the adhesive driven into and spread on the edge and extended to the edges of the centermost pages which extend beyond the hinge line of book when opened.

The operations described may be performed by the 30 apparatus illustrated in Figure 12, wherein the clamping jaws 20 and 21 may be moved toward each other by suitable toggle links 28. The bed or machine base 29 is provided with pivotal standards or levers 30 and 31, having counterbalancing weights 32 and 33. These 35 standards are provided with slide guides 34 and 35 in which ride the slide shoes 36 and 37. The shoes are formed on the outer faces with rack teeth 38, engaged by the gears or pinions 39. These pinions are on a short counter-shaft 39a keyed to a worm gear 40 which in turn is coupled with the worm wheel 41, driven by the 40 cross shaft 42 to be turned for operation by the hand wheel 43. The shoes 36 and 37 provide bearings to trunnion the roll 44 revolvably which are supported at the hubs 45 thereof. The roll 44 is supplied interiorly with a heating coil 46 mounted on the centrally positioned arbor 47. The leads 48 are directed through the shoe 36 to a suitable source of electric current, thus providing means for electrically heating the roll 44 at a temperature to transmit rolling heat of 200° F.

50 A cross bar 49 is connected to the ends 50 of the standards or levers 30 to permit manual rolling of the roll 44 over the stack in the clamp jaws 20 and 21. However, it will be understood that prime movers may be used to secure the tilting movement to direct the 55 roll 44 to the positions illustrated in Figures 9 and 10.

Upon completion of the rolling steps, the action serves to rub the paper to unite all of the layers of adhesive to the back of the stack. The heat and pressure serve to set the adhesive to the thermally unaffected state of 60 plasticity at the prescribed temperature, uniting the sheets, including the innermost pages, and through the crash and to the backing. Within two seconds after this step is performed, the book is ready for "casing-in" by the usual procedure and need not be stacked as is the present 65 practice with glue bond booking adhesive.

By my process and with the apparatus described, five steps quickly executed are necessary to prepare the book and make it ready for "casing-in." This may be contrasted with present known operations for book binding 70 to achieve relatively the same condition and which involve:

1. Sewing or sawing;
2. Applying the wet glue;
3. Drying;

4. Backing with the back former and rounding;
5. Applying a second coating of wet adhesive;
6. Applying crash or super;
7. Gluing over crash of another wet adhesive;
8. Applying head bands and paper backing;
9. Rubbing paper to unite all layers;
10. Drying by air or force drying;
11. Storing to set adhesive before "casing-in."

The foregoing prior art operations may take from twenty to thirty minutes, where forced drying is employed, or to several hours if provisions for forced drying are not available, and storage facilities must be provided before the "casing-in" operation is performed.

It will be understood that while I have shown and preferred the perforation of the paper to produce the fold 11 by a perforating device known to produce a "wind" perforation made by a continuous winding of the web through perforating rolls, in that this form of perforation leaves the incised segments with serrated edges to some extent but not preferred, the alternate incisions may be knife-cuts followed by abrasions employing a suitable abrading device, to level off the edges of the pages in each signature to expose the edges of the pages at the inner fold and make them accessible to the adhesive to be applied.

It will also be understood that while I have described initially the step of drying the adhesive films 24 and 27 by air or forced drying (circulating dry or warmed air) before applying the heat and pressure as described by me, I may only partially dry the adhesive. The adhesive for the film 24 need only be dried sufficiently so that the pages will not shift out of place. Drying to retain a residual amount of water of from 10% to 25%, preferably 10% has been found adequate for my purpose at this stage. Likewise, in applying the backing strip 26 with the adhesive film 27, the film need not be dried before applying the heat and pressure by the roll 44, since the sheet 26 acts as a separator permitting direct contact of the back thereof, with the roll 44 to dry and set the adhesive at temperatures below the scorching point of the paper, and preferably at 200° F. as described.

It will be observed that in accordance with the method described and the apparatus as described, five steps executed as follows, are involved:

1. Stacking sewn or perforated signatures;
2. Film coating back;
3. Partially drying;
4. Applying crash and adhesively coated (partially dried or wet) paper backing carrying headbands;
5. Rubbing under heat and pressure simultaneously to unite all layers.

These five steps permit the book to be "cased-in" within two seconds, as compared with the eleven steps heretofore outlined, as performed by the prior book binding procedure with wet glue.

It will be observed that while I have described the application of the adhesive to a stack of clamped signatures, it is contemplated by me that the glueing operation initially applied may be to a group of unclamped signatures, singly or groups of such stacks, and thereafter initially drying to retain the residual moisture as indicated, but to permit manual handling without shifting and then removing such stacks to the device hereinbefore described for applying the crash, paper, etc. for the heat and pressure steps described.

Having thus described my invention and illustrated its use, what I claim as new and desire to secure by Letters Patent, is:

1. In the method of book binding a stack before "casing-in" which includes the steps of coating a thermo-plastic adhesive film in an aqueous suspension on the back of a stack of pages overlying a crash and backing layer and then simultaneously spreading the adhesive

under heat and pressure on the edge of the stack and about the edges and side of the pages by rounding, to set the adhesive to a heat irreversible state of plasticity below 200° F.

5. 2. In the method of book binding a stack of signatures before "casing-in" which includes the steps of clamping a stack of signatures, the fold line of each of which signatures having "wind" perforation, coating an aqueous emulsion of a thermo-plastic synthetic plastic on the stack, 10 drying to the point where the signatures will not move out of place without setting the coating, applying a layer of crash and a backing strip and rubbing the backing strip to the composite of crash and adhesive, to unite the backing strip and pages to each other under heat and pressure to flare the stack and distribute by rounding and to set the adhesive to a heat irreversible state of plasticity below 200° F.
- 15 3. In the method of book binding which includes stacking signatures with the back fold having wind perforations substantially co-terminous, clamping the stack to leave an overhang unclamped, levelling the edge of the stack by abrasion to expose the edges of the pages at the inner fold, coating the backing of the stack on the back fold with an aqueous emulsion of a polymerized vinyl compound, partially drying the adhesive so applied, superimposing a sized crash and backing strip carrying an adhesive and then rolling the backing to distribute the adhesive while simultaneously heating the adhesive, the signatures being rolled to flare or fan the overhanging 20 back folds to spread the adhesive on the edge and about the sides of the signature to simultaneously unite the backing strip and signature to the crash and set the adhesive.
- 25 4. In the method of book binding a stack of signatures before "casing-in," employing paper which is sized, coated, calendered, which includes providing the signatures with back fold having "wind" perforations, clamping the fold so formed, levelling the edge of the stack by abrasion to expose the edges of the pages at the inner fold, 30 coating the backing of the stack with an aqueous emulsion of a polymerized vinyl compound capable of being set by heat and pressure to a heat irreversible state of plasticity within limits of 200° F., partially drying the coating so that the signatures will not shift out of place 35 when manually handled while retaining residual moisture of from 10% to 25%, applying crash having a water activatable size, superimposing a backing strip carrying an adhesive comprising an aqueous emulsion of a heat settable polyvinyl acetate and then simultaneously applying heat and pressure to set and merge the adhesive layers.
- 40 5. A method in accordance with claim 4 wherein the heat and pressure are applied by a rolling action to flare the stack of signatures and distribute the adhesive on 50 and about the edges of the signature and sides thereof.
- 45 6. In the method of book binding before "casing-in" which includes the steps of forming on a group of signatures a back fold having wind perforations and folding the same about said row of wind perforations, arranging the folds substantially co-terminously to form the book back and levelling the edges by abrading to expose the edges of the pages at the inner fold, clamping the stack so formed leaving an overhang unclamped, applying a layer of a thermo-plastic adhesive, partially drying 55 the adhesive, overlying a strip of crash, a layer of adhesive and a backing strip, rubbing to round the backing strip to the stack under heat and pressure to distribute the adhesive and to set the same to an irreversible state of plasticity at temperatures below 200° F. uniting the 60 crash and backing strip to each other and to the edges of the signatures, the rubbing pressure under heat being extended to distribute the adhesive through the perforations, to reach the inner pages of the signatures.
- 65 7. The method of binding books before "casing-in" 70 which includes the steps of forming signatures and pro-

viding wind perforations in the last back fold, stacking the signatures with said fold co-terminously and levelling the edges by abrading to expose the edges of the pages at the inner fold, clamping said stack to leave an overhang, applying an emulsion of a high polymer polyvinyl acetate in an aqueous suspensoid including a plasticizer and an accelerator, said emulsion having a viscosity of 250 to 350 centipoises, partially drying the adhesive to leave a residual moisture of from 10% to 25%, overlying a strip of crash sized with a water compatible adhesive and another layer of the adhesive and backing strip, applying heat and pressure to set the adhesive and to distribute the adhesive on the edge and about the sides of the signature to direct the adhesive through the perforations to the center pages of the signature and to round the overhang.

8. In the method of binding books before "casing-in" which includes stacking back folded signatures having wind perforations in the fold and levelling the edges by abrading to expose the edges of the pages at the inner fold, clamping the stack to expose the back forming portion and applying a layer of thermoplastic adhesive which under heat is convertible to a heat irreversible state of plasticity at temperatures below 200° F., applying a layer of crash and a back cover strip and uniting the strips to the stack of signatures under heat and pressure, to distribute the adhesive into the perforations of the back fold and to set the adhesive to a heat irreversible state of plasticity below 200° F. but to remain thermo-plastic above such temperature.

9. A process in accordance with claim 8 wherein the wind perforations leave a serrated edge on the disconnected edges of each signature.

10. In the method of book binding before "casing-in" which includes clamping back folded signatures, each having wind perforations in the fold and levelling the edges by abrading to expose the edges of the pages at the inner fold, to leave an overhang, applying a layer of thermoplastic adhesive and a strip of crash, superimposing a back cover strip and rolling the strip into uniting position to flare the back folded edges and to distribute the adhesive about the edges and sides of the signatures and into the perforations to reach the edges of the center pages and to set the adhesive.

11. In the manufacture of books, the steps of establishing a book block consisting essentially of a multiplicity of separate leaves and having a smooth back edge surface wherein an edge portion of each leaf is squarely exposed at the level of said surface, applying to said back edge surface and in edgewise adhesive engagement with each said leaf a water-insoluble adhesive in a flowable form to constitute an adhesive layer extending across said back edge surface, and thereafter and while said adhesive is in an at least partially plastic state, rounding and backing the book block by mechanical deformation of its back edge surface to provide said block with a rounded hinge-defining configuration which is adapted for application of a hard casing to the block, said rounding and backing operation including flaring the leaves of the block toward each side of the back edge surface to constitute ridges at the sides of said surface for providing said hinge-defining configuration, and said adhesive thereafter setting to maintain the said configuration with the leaves bound together by the said adhesive at their back edges.

12. In the manufacture of books, the steps of establishing a book block consisting essentially of a multiplicity of separate leaves and having a smooth back edge surface wherein an edge portion of each leaf is squarely exposed at the level of said surface, applying to said back edge surface a thermo-plastic, water-insoluble adhesive layer extending across said surface in adhesive engagement with each of the leaves edgewise thereof, and thereafter and while maintaining said adhesive sufficiently

plastic to permit its yielding without rupture of said layer, displacing the leaves relative to each other to constitute a rounded back edge surface and flaring the leaves toward each side of the back edge surface to constitute hinge-defining ridges at the sides of said surface, to provide a rounded and backed block adapted for application of a hard casing thereto, said adhesive layer thereafter setting to hold said back edges of the leaves in the rounded and flared configuration.

13. In the manufacture of books, the steps of establishing a book block consisting of a multiplicity of separate leaves having a smooth back edge surface in which an edge portion of each component leaf is squarely exposed, applying to said back edge surface an insoluble thermo-plastic adhesive dispersed in a water emulsion thereof and adapted to penetrate edgewise into each leaf, drying the adhesive to solidify the same, rounding and backing said back edge surface by mechanical deformation with the adhesive at an elevated temperature which renders it yieldable against rupture of its adhesive bond, said rounding and backing operation providing the book block with a rounded, hinge-defining configuration which is permanently maintained when the adhesive is fully cooled and set and which is adapted for application of a hard casing to the block, and said rounding and backing operation including flaring the leaves of the block toward each side of the back edge surface to constitute ridges at the sides of said surface for providing said hinge-defining configuration which is maintained as aforesaid when the adhesive is set.

14. In the manufacture of books, the steps of establishing a book block consisting of a multiplicity of separate leaves having a smooth back edge surface in which the edge of each component leaf is squarely exposed, applying to said back edge surface an insoluble thermo-plastic adhesive dispersed in a water emulsion thereof and adapted to penetrate edgewise into each leaf, drying the adhesive to solidify the same, rounding and backing said back edge surface by mechanical deformation with the adhesive at an elevated temperature which renders it yieldable against rupture of its adhesive bond, said rounding and backing operation providing the book block with a rounded, hinge-defining configuration which is permanently maintained when the adhesive is fully cooled and set and which is adapted for application of a hard casing to the block, and said rounding and backing operation including flaring the leaves of the block toward each side of the back edge surface to constitute ridges at the sides of said surface for providing said hinge-defining configuration which is maintained as aforesaid when the adhesive is set.
